LOCKING HOLDER

Oles B. Jacobs, Melrose Park, Ill.

Application December 2, 1948, Serial No. 63,117

7 Claims. (Cl. 24-3)

1

This invention relates to improvements in locks for securing pens and pencils and small tools within a holder adapted to be attached either within a skirt or coat pocket.

An object of the invention is to provide an improved lockable holder for pens, pencils and small articles such as tools, said holder being adapted for attachment within or on the upper edge of a pocket, for preventing theft of the writing implements and tools when once locked within the holder.

Another object of the invention is to provide an improved self-locking holder for supporting and securing writing implements and tools, said holder being formed with means for detachably supporting the holder within a pocket or upon the upper edge thereof.

A further object of the invention is to provide an improved lockable holder for writing implements and tools which will be highly efficient in use and relatively inexpensive to manufacture and produce.

Other objects will appear as the description proceeds.

In the accompanying drawings which form a part of this application:

Figure 1 is a front elevation of the locking holder with cover closed.

Fig. 2 is a front elevation of the locking holder with cover open.

Fig. 3 is a rear elevation of the locking holder with the cover closed.

Fig. 4 is a top view of the locking holder with the cover open.

Fig. 5 is a sectional view taken on the line 5-5 of Fig. 2.

Fig. 6 is a sectional view taken on the line 6-6 of Fig. 2.

Fig. 7 is an exploded view of the locking mechanism of the holder shown in Fig. 2.

Fig. 8 is a view of the inside top portion of the front plate of the holder, showing two additional modified forms of locking mechanisms.

Fig. 9 is a perspective view of one of the locking mechanisms shown in Fig. 8.

Fig. 10 is a perspective view of the other of the locking mechanisms shown in Fig. 8.

Fig. 11 is a sectional view taken on the line 11-11 of Fig. 8.

Like characters of reference are used throughout the following specification and the accompanying drawings to designate corresponding parts.

In carrying out the invention, there is shown and provided an improved form and construction

2

of locking holder for small articles such as writing pens and pencils, or small tools.

The holder comprises a substantially flat base plate 1 and a cover plate 2 hinged at 3 to said base plate 1 adapted to lie in parallel spaced relation therewith when in operative position, and capable of being swung at right angles thereto when it is desired to have access to the locking devices or mechanisms supported upon the base plate 1, said locking devices being hereinafter more fully described.

Means for attaching the holder cover plate 2 over the top of a pocket (not shown) either within the pocket or in front thereof, consists of the inverted U-shape supporting hooks 4 and 5 disposed in spaced relation to the upper edge of the cover plate 2, being secured to the upper and outer corners of said plate 2. The hooks 4 and 5 are connected together by the clamp bar 6 disposed transversely of the inner surface of the cover plate 2, and will be used for supporting a shop card or other identification card (not shown).

A transversely extending actuating shaft 7 will be rockably supported along the upper edge of the cover plate 2, and will be formed with integral C-shaped fabric engaging and piercing hooks 8 and 9 disposed between the arm portions of said hooks 4 and 5, with the pointed ends of said C-shape hooks 8 and 9 resiliently held in contact against the outer surface of the cover plate 2 by means of the leaf spring 10 attached at 11 to the inner surface of the cover plate 2, extending upwardly to a point above the top thereof and being in resilient contact with the integral hook-releasing loop 12 formed midway of the shaft 7 and extending upwardly therefrom. It will be seen that the holder will be positioned to have the hooks 4 and 5 overlie the top edge of a pocket while the C-shape hooks 8 and 9 are swung away from the back plate 2 by forcing inwardly upon the loop 12 against the tension or pressure of the spring 10. When the loop 12 is released, the pointed ends of the C-shape hooks 8 and 9 will pierce the fabric of the pocket to lock or secure the holder in operative position.

The base plate 1 is substantially rectangular in shape and supports the transversely extending guide plate 13 along one side thereof at its bottom end by means of the inwardly directed flanges 14 formed at the opposite sides of the plate 1. Transversely spaced guide ears 15 are formed integrally with the guide plate 13 for properly spacing the lower ends of the writing implements 16 when supported by the holder.

In Figs. 1 to 7 inclusive, the base plate is provided with a transversely extending guide plate 17 secured by rivets 18 to the upper and opposite surface of said plate from the guide plate 13. The guide plate 17 is formed with a plurality of transversely spaced arcuate holding loops 19 in which the pocket attaching clips 20 on the writing implements 16 are adapted to be inserted and secured.

A transverse slot 21 is formed through the end of the guide plate 17 adjacent the hinge 3, and cooperates with a locking detent or finger 22 supported by the upper end of the leaf spring 23 attached by the rivet 24 to the lower portion of the plate 1. The locking detent 22 will be pulled from the slot 21 for the insertion of a flat implement (not shown) placed between the plate 1 and spring 23, and the tension of said spring 23 will force the detent 22 into firm holding engagement with the implement.

A second locking detent 25 will be pivotally supported at 26 to the plate 1 below one of the holding loops 19 and will be provided with locking lips 27 for engaging the clip 20 on a writing implement 16 when in the loop 19 for preventing its removal until the lower end of the actuating lever 28 pivoted at 29 upon the plate 1 is cammed into engagement therewith for releasing the clip 20. A spring 30 is secured at one end to the ear 31 struck from the plate 1 and has its other end attached to the upper end of the lever 28 for holding the same under resilient tension.

A third form of locking detent comprises the locking member 32 pivoted at 33 to the plate 1 and formed on its upper end with a cam locking lip 34. An actuating lever 35 is pivoted at 36 to the upper end of the plate 1, and has its lower end pivotally connected at 37 to the locking member 32, and is further formed with the U-shape cam actuating shoulders 38 for engaging the cam locking lip 34 for locking and releasing the same.

Obviously the actuating levers will be manually moved in one direction for locking the implements in the loops 19, and will be moved in the opposite direction when releasing the implements.

In Figs. 8 to 11 inclusive, additional forms of locking mechanisms are shown and include the base plate 1 having transversely extending guide strips 13 and 17 secured respectively to the opposite bottom and top surfaces thereof, and formed with the guide ears 15 and locking loops 19, as hereinafter described.

An actuating and locking lever 39 is pivoted at 40 to the guide plate 17 and lies between the same and the base plate 1. A tensioning spring 41 is secured at one end to said lever 39 and has its opposite end anchored in the jaw member 42, which cooperates with the arcuate jaw 43 formed on the lower end of the lever 39 for holding the clip 20 of a writing implement 16 in locked position when inserted in the loop 19.

A transverse guide channel member 44 is secured to the plate 1 and slidably supports the flanged locking plate 45 formed with spaced locking flanges 46 and 47. An ear 48 is formed on the plate 45 and is apertured at 49 to receive the lower end of spring 50 supported by the actuating lever 51 pivoted at 52 to the guide plate 17, whereby movement of the lever 51 in one direction will slide the plate 45 to lock the clips 20 of implements

16 in the other loops 19, and the reverse movement of the lever 51 will release said implements. A loop 52' formed by the upper end of the spring 50 provides a means for slipping over a button (not shown) for supporting the holder if desired.

While the preferred embodiment of the instant invention has been illustrated and described, it will be understood that it is not intended to limit the scope of the invention thereto, as many minor changes in detail of construction may be resorted to without departure from the spirit of the invention.

Having thus described my invention what I claim as new and desire to secure by Letters

15 Patent of the United States is:

1. A locking holder for implements including a base plate and a cover plate hinged thereto, supporting means for said holder mounted in said cover plate, guide plates on said base plate, implement supporting loops on said guide plates, and locking detents for said implements pivotally mounted upon said base plate.

2. A locking holder for implements including a base plate and a cover plate hinged thereto, supporting means for said holder mounted on said cover plate, guide plates on said base plate, implement supporting loops on said guide plates, implement locking detents pivotally mounted upon said base plate, and actuating levers pivotally mounted upon said base plate having operative engagement with said locking detents.

3. A locking holder for implements including a base plate and a cover plate hinged thereto, supporting means for said holder mounted on said cover plate, guide plates on said base plate, implement supporting loops on said guide plates, implement locking detents pivotally mounted upon said base plate, and actuating levers pivotally mounted upon said base plate having camming engagement with said locking detents.

4. A locking holder for implements including a base plate and a cover plate hinged thereto, supporting means for said holder mounted on said cover plate, guide plates on said base plate, implement supporting loops on said guide plates, implement locking detents pivotally mounted upon said base plate, actuating levers pivotally mounted upon said base plate having camming engagement with said locking detents, and resilient tensioning means for said actuating levers.

5. The subject matter as claimed in claim 4, and pivotally mounted oppositely disposed attaching hooks on the upper edge of said cover plate.

6. The subject matter as claimed in claim 4, pivotally mounted oppositely disposed attaching hooks on the upper edge of said cover plate, and inverted U-shape supporting hooks disposed at the opposite edges of said cover plate overlying said attaching hooks.

7. The subject matter as claimed in claim 4, pivotally mounted oppositely disposed attaching hooks on the upper edge of said cover plate, inverted U-shape supporting hooks disposed at the opposite edges of said cover plate overlying said attaching hooks, and a transverse identification card retaining bar connected between said supporting hooks on the inside of said cover plate.

OLES B. JACOBS.
